[57] CLAIM

The ornamental design for a porthole parachute plaything for group activity, as shown and described.

DESCRIPTION

FIG. 1 is a top perspective view of a porthole parachute plaything for group activity showing my new design; FIG. 2 is a bottom plan view thereof;

FIG. 3 is a side elevational view thereof, all sides being identical;

FIG. 4 is a front elevational view thereof;

FIG. 5 is a front elevational view thereof, in an alternate position; and,

FIG. 6 is an enlarged partially broken away perspective view thereof.

The broken line showing of children in FIGS. 4-6, are for illustrative purposes only and form no part of the claimed design.
